UNITED STATES PATENT OFFICE.

FRANZ A. FULLER, OF NEWARK, NEW JERSEY.

SAFETY-RAZOR.

1,197,364.

Specification of Letters Patent. Patented Sept. 5, 1916.

Application filed December 29, 1913. Serial No. 809,196.

To all whom it may concern:

Be it known that I, FRANZ A. FULLER, a citizen of the United States, residing in the city of Newark, in the county of Essex and State of New Jersey, have invented certain new and useful Improvements in Safety-Razors, of which the following is a full, clear, and exact description, such as will enable others skilled in the art to which it pertains to make, construct, and use the same, reference being had to the accompanying drawings, and to numerals of reference marked thereon, forming a part of this specification.

15 This invention relates to safety razors in which a detachable razor blade of novel construction is designed to be readily and efficiently secured to a device, in which a razor blade support is employed, which in general 20 appearance resembles what is commonly known as a "straight razor", and further providing the same with a guard for the exposed edge of the razor blade, the guard being so constructed that, if desired, it may be 25 applied to one side or the other of the razor blade support, or if desired, it may be dispensed with entirely.

An important feature of the invention is to so construct the razor blade support, and 30 its attached razor blade clamping means, that a razor blade of novel construction may be readily secured thereto or removed therefrom, thereby providing a device resembling an ordinary straight razor, in which a 35 detachable blade is to be used, thus insuring a sanitary shave, it being understood that a blade may be used once and then discarded if desired.

With this end in view, my invention consists in certain novelties of construction, and 40 arrangements of parts as hereinafter set forth and pointed out in the claims.

While the preferred forms of my invention are illustrated in the accompanying 45 drawings, yet it is to be understood that minor detail changes may be made without departing from the scope thereof.

In the accompanying drawings, Figure 1 represents a side elevation of a razor embodying my invention. Fig. 2 represents a transverse section of the blade support, razor blade and razor clamping means, taken on lines $x-x$ of Fig. 1. Fig. 3 represents a fragmentary side elevation of the razor 55 blade support, and the razor blade clamping means pivotally connected thereto. Figs. 4

and 5 represent respectively, side and end elevations of the razor blade. Fig. 6 represents a side elevation of a razor embodying my invention, with a guard secured 60 thereto. Fig. 7 represents a rear elevation of the guard. Figs. 8 and 9 represent respectively a perspective view of a fragment and a front elevation of the same; and Fig. 10 represents a modified form of razor blade 65 support.

Similar numerals of reference refer to like parts throughout the specification and drawings.

In the drawings, 1 designates a casing of 70 ordinary form to which the curved extremity of the shank 2 of the razor blade support 3 is pivoted at 4. The detachable razor blade 5 is made of sheet steel and provided with a substantially plane portion 6 along 75 one longitudinal edge, said blade having a single longitudinal cutting edge 7 on the side opposite said plane portion 6, the blade intermediate said portion and said cutting edge, comprising a uniformly concaved portion 8 on which the cutting edge is formed, and which lies entirely on one side of the central plane of said first-mentioned portion, and an offset portion 9 connecting said concaved portion with said first-mentioned portion. 85

The razor blade support 3 is preferably made in the form illustrated in cross-section in Fig. 2 of the drawings, and provided with a shoulder 10, so that a razor blade as 90 above described may be conveniently positioned on either side of said support 3, and effectively held in position thereon by means of the channel-shaped clamping element 11, one end of which is pivotally secured to the shank of the razor blade support as at 12. The channel-shaped clamping element 11 at 95 one end thereof, as at 14 is closed, which closed end, together with the shoulder 10 on the razor blade support 3, provides means to prevent longitudinal displacement of the razor blade, at the same time securely locking the blade to the blade holder.

My invention, so far described, is designed 105 to perform the same functions as the hollow-ground straight razor, so commonly used. In order that the device may be employed as a safety razor, I provide a detachable guard plate designed to be applied to one side or the other of the razor blade support. The razor blade guard consists 110 essentially of three elements, namely, the

guard plate 15 which is slidably secured to a channel-shaped support 16, said support being designed to have sliding engagement with the clamping element 11, and a flat 5 spring 17 secured to the inside of the channel shaped support 16 and designed to have frictional engagement with the top of the clamping element 11 and by means of which the guard is securely clamped to the razor 10 blade support 3 and the razor blade 5. The guard plate 15 is constructed to grip the blade 5 at the front corners, the sharpened edge of the blade resting upon the bent-over end of the guard plate 15, which is provided 15 with the usual perforations 18, the free end of which is bent downwardly and which is sufficiently in advance of the end of the blade to afford the necessary protection against accidental cutting. The ends of the 20 guard plate 15 are provided with upwardly extending stops 19 for engagement with the corners of the cutting edge of the blade 5, to prevent said cutting edge from projecting too far beyond the guard 15 to at all 25 times maintain the cutting edge of the razor blade in the proper and adjusted position relative to the guard teeth. These stops 19 may, for convenience' sake, be formed integral with the guard plate 15 or secured 30 thereto in any convenient manner. As illustrated in Fig. 8 of the drawings, the guard plate has approximately the shape of the razor blade.

Secured to the guard plate 15 are pins or 35 studs 20 designed to engage with the angularly-arranged elongated slots 21 formed in one side of the channel-shaped support 16, which is slidably secured to the guard plate 15, as clearly illustrated in Fig. 9 of the 40 drawings, so that when the channel-shaped support 16 is in the position relative to the guard plate 15, as illustrated in said figure, the cutting edge of the razor blade is brought into engagement with the stops 19 45 of the guard plate, and the channel-shaped support 16 is moved in the direction indicated by the arrow in Fig. 6 of the drawings, thereby securing the guard to the razor blade support and blade. The channel-shaped support 16 is of such dimensions 50 and configuration as to fit over and have sliding engagement with the clamping element 11. Located within said support and extending the entire length thereof, is a flat 55 spring 17, to which is secured in any convenient manner, a headed stud 23 extending through the top of the support and which at all times maintains the spring in its proper position, said spring, together with 60 the support 16, serving to maintain the guard in its adjusted position.

24 represent studs of any convenient form, secured to the ends of the support 16 to enable said support to be moved relative to the guard plate.

In Fig. 10 of the drawings, I have shown a modified form of a razor blade support 25, designed to support a flat razor blade 26 and which consists in providing the razor blade support 25 with an additional removable clamping plate 27 of approximately the same shape as that portion of the razor blade support 25 to which the plate is secured, which clamping plate 27 is secured to the razor blade support 25 by means of 75 studs 28, which are secured to the support 25 and which pass through suitable apertures in the razor blade 26 and designed to enter suitable apertures in the detachable clamping plate 27, all of which are held 80 together by the clamping element 11, in substantially the same manner as heretofore described.

Although I have illustrated the preferred form of my invention, I do not care to be 85 limited to the exact details of construction as shown and described, as obvious modifications thereof will appear to those skilled in the art.

I claim:

1. A razor, comprising a razor blade support transversely concaved on both sides, and provided with a substantially plane portion along one longitudinal edge, and an offset portion connecting said concaved portion with the plane portion, a detachable concaved razor blade mounted on one side of said support, and clamping means pivotally secured near one end of said support for securely clamping the blade to the said 95 plane portion of the longitudinal edge of said razor blade support.

2. A razor, comprising a razor blade support provided with shoulders near one end thereof and transversely concaved on both 105 sides, and further provided with a substantially plane portion along one longitudinal edge, and an offset portion connecting said concaved portion with the plane portion, a detachable concaved razor blade mounted on one side of said support, and channel-shaped clamping means pivotally secured 110 near one end of said support for securely clamping the blade to the said plane portion of the longitudinal edge of said razor 115 blade support.

This specification signed and witnessed this 27th day of December, 1913.

FRANZ A. FULLER.
